UNITED STATES PATENT OFFICE.

WILLIAM H. KNOWLES, OF PORT CHESTER, NEW YORK, ASSIGNOR, BY MESNE ASSIGNMENTS, TO GENERAL BOTTLE CAP CORPORATION, OF PORT CHESTER, NEW YORK, A CORPORATION OF NEW YORK.

CLOSURE.

Application filed August 30, 1924. Serial No. 735,081.

This invention relates to a receptacle closure, and aims to provide a device of this character particularly adapted for use in connection with the sealing of receptacles of 5 the milk bottle type.

It is an object of the invention to provide a closure of improved construction which may readily be applied to a receptacle by an inexperienced person, and by means of a 10 simple form of tool so that by the practice of the present invention it becomes unnecessary to utilize a large and expensive outlay of apparatus, thus enabling a relatively small dairymen or other user to readily employ the closure.

A further object of the invention is that of providing a device of the character stated, which, when in applied position, will serve to furnish a positive seal, thus preventing the 20 entrance of foreign matter into the receptacle, or the spillage of any of the contents of the latter.

A still further object is to be predicated on the furnishing of a closure which will be of 25 such a nature, and applied in such a manner, that the danger of receptacle breakage is reduced to a minimum.

Another object of the present invention embraces the thought of providing a closure 30 which will not accidentally become unsealed, but which, when desired, may readily be opened without injury to the fingers.

Still another object is that of providing an improved closure preferably of such a 35 nature that when the same is once opened it may be readily detached, or, in fact, will be practically automatically removed from the receptacle with which it is associated, so that upon the return of the latter for the 40 purpose of cleansing, refilling and resealing, no time will be lost in the removal of the previously used seal.

An additional object is that of providing 45 a closure which will efficiently perform the purposes for which it is intended, and which will also be economically and readily manufactured and assembled.

Other objects of the invention will in part 50 be obvious and will in part appear herein-after.

The invention accordingly comprises an article of manufacture possessing the features, properties, and the relation of elements which will be exemplified in the article here-

in after described and the scope of the application of which will be indicated in the claims.

For a fuller understanding of the nature and objects of the invention reference should be had to the following detailed description taken in connection with the accompanying drawings, in which:

Fig. 1 is a side elevation of a receptacle neck having applied thereto one form of closure constructed within the terms of the present invention;

Fig. 2 is a plan view of a part of the closure member prior to the application thereof to a cap;

Fig. 3 is an enlarged sectional plan view 70 of the separated ends of one portion of the closure member;

Fig. 4 is a similar view, illustrating these end-portions in joined position;

Figs. 5 and 6 are transverse sectional views 75 taken along the lines 5—5 and 6—6, respectively, and in the direction of the arrows indicated in Fig. 2;

Fig. 7 is a view similar to Fig. 4, but showing a slightly different construction 80 which may be resorted to, if desired; and

Figs. 8 and 9 are fragmentary side elevations of closure member portions.

Referring primarily to Fig. 1 it will be noted that the invention has been shown as 85 used in connection with a receptacle of the milk bottle type. It will be appreciated, however, that a closure of the nature herein-after described will lend itself for use in connection with widely varying types of receptacles, and for numerous different purposes.

Thus, the reference numeral 10 indicates the neck of a bottle, which is formed with a lip 11 adjacent its mouth. In order to close 95 this outlet portion of the receptacle a cap of any desirable material may be employed, which includes a depressed or cup-shaped central portion 12, a body 13 and a skirt-portion 14. A cap of this type is, in many 100 respects, particularly advantageous, in that by using the same it is not necessary to employ an inner seal in addition to the cap, it being understood that heretofore it has been customary to utilize a supplemental sealing member in the nature of a disk of material.

More particularly it will be found that by employing a cap of the nature aforede-

scribed the base of the cup-portion 12 lies adjacent the inwardly-extending annular flange 15 which usually forms an integral part of the receptacle body. The side walls 5 of the cup-portion will also be found to bear intimately against the inner walls of the receptacle neck at points above the flange 15, while the cap body 13 firmly envelopes the lip 11. The skirt-portion 14, when engaged 10 by a proper type of closure member, serves to retain all parts of the cap in the positions aforementioned, and it has been found in actual practice that where this form of construction is employed an extremely desirable 15 seal is provided, which possesses all the advantages of the cap commonly used at present, while having none of the disadvantages of the same.

The present invention concerns itself, however, to a great extent with that portion of a closure member which serves as a seal. In the present instance, this member is in the nature of a split band having a flat body 16, preferably formed of a somewhat bendable 25 material and curved in shape so that its ends may be readily brought to points adjacent each other. These ends are preferably in the nature of offset portions 17 and 18, respectively, and in the formation of these portions 30 flanges 19 may be provided, which extend between the side edges of the band body and the end-portions thereof, and serve to sufficiently rigidify the parts to thus prevent an accidental unbending of the end-portions.

35 Now, with the view of connecting these end-portions together it will be noted in the present exemplification that the part 17 is formed with an opening 20 of a diameter sufficient to accommodate a collar 21, which 40 forms a part of the end-portion 18. In practice this collar is passed through the opening 20, and is subsequently bent to extend outwardly at portions adjacent its edge, whereby it is prevented from being retracted 45 through the opening aforesaid.

With the view of providing means serving to prevent a breakage of the receptacle upon one of the closure members being applied thereto it will be noted, as has been clearly 50 illustrated in Fig. 2, that the body 16 of the band may be formed with one or more series of corrugations 22. These corrugations are obviously formed in the band prior to its application to the cap or other element with 55 which it is associated. Thus, assuming that the closure member is being used in conjunction with a cap of the nature illustrated in Fig. 1, the latter may be applied to the mouth of the receptacle, and the band constituting 60 the closure member may be subsequently applied to the cap skirt-portion, and if by means of a suitable and relatively simple tool the ends 17 and 18 are now drawn together, it will be understood, assuming that the diameter 65 of the receptacle neck is such that the

band is incapable of completely encircling the same the corrugations forming a part of the portion 22 will be stretched so that the effective length of the band is lengthened, whereupon the collar 21 will be free to enter 70 the opening 20, subsequent to which the tool may flare the outer edge portions of this collar outwardly in the manner indicated in Fig. 4, so that the parts will be locked against accidental removal.

75 In this connection it is to be noted, as a matter of fact it is preferred, that the effective length of the closure member be such as to be inadequate to completely enclose the neck of the receptacle, so that in each instance it will be necessary for the corrugated portions to be stretched in order to seal the closure member. In fact, it is in most instances desirable to have the effective length of this retaining means slightly less than the 80 girth of the receptacle at the point of application of the former to the latter, it being understood that by this expedient the cap portion of the closure is virtually anchored in position. The amount of the stretching 85 will of course vary, incident to the variations in the size of the individual receptacles, but in no instance will this stretching affect the tightness of the seal provided in that, first, the corrugated portions are relatively stiff, and secondly, the band, being preferably of a somewhat resilient material, will tend to resume its original effective length, which will necessarily result in an extremely tight 90 seal being formed. Furthermore, it has been noted that, incident to providing a band which will accommodate itself to variations in the diameter and contour of a receptacle portion, the latter will at no time become 95 broken during the application of the closure, thus avoiding one of the major objections to closures as heretofore utilized in connection with milk bottles or similar receptacles.

100 It will be obvious that with the closure member mounted, a previous opening thereof will be immediately apparent in that the retaining member which forms a part of the closure and serves to secure the cap in position upon the receptacle will have been 105 broken. On the other hand, if it is desired to open this closure this may readily be accomplished in a number of desirable manners. For example, assuming that the member embraces the construction disclosed in Figs. 1 to 6, inclusive, it will be merely necessary to introduce the point of an ice-pick, prong of a fork or other desirable implement through the opening or bore of the collar, and to slightly swing this implement. This action 110 will cause the band ends to be twisted, which will result in the parts tearing or in the collar being forcibly retracted from its position 115 within and beyond the opening 20.

120 Likewise, a knife or similar instrument may be utilized to open the closure member, in that 125

an instrument of this nature may be moved to occupy a position at which its edge will extend between the opposing faces of the end-portions 17 and 18, whereupon, by slightly twisting the implement utilized (in order to obtain a lever action), these parts may be forced apart. In order to simplify this action the end-portions 17 and 18 may be joined in such a manner that a decided space exists between their outer faces at points adjacent their upper edges, this having been indicated at 23 in Fig. 7. By this expedient the introduction of a proper implement into the space aforementioned is greatly facilitated, and consequently, the operation of opening the closure member in the last described manner is somewhat expedited.

In certain instances, where it is not desired to utilize an implement in the manner aforementioned, the opening of the closure member may be effected by incorporating a rupturable point in the band. Thus, in Fig. 8 it will be noted that a pair of opposed V-shaped notches 24 have been shown, which notches, although serving to weaken the band at this point, nevertheless do not sufficiently impair the strength of the band so that an accidental loosening of the same would result. Nevertheless, a prong of a fork or a similar implement may be placed adjacent the base of one notch and moved so that the strip will readily rupture through to the other notch. Likewise, if desired, as in Fig. 9, the band body may be formed with an opening 25, from one end of which diverging score-lines 26 extend. Thus, by simply gripping and pulling those portions of the band which are between the score-lines the band will again be ruptured.

In any event, and regardless of how the band is opened, it will be noted that when once opened the fact of such opening is readily apparent to anyone glancing at the receptacle. Also, it will be impracticable for a person to endeavor to reconnect the parts without this fact being immediately perceptible, and the closure member will in the natural course of events be detached from the receptacle, so that when the latter is returned for refilling it does not become necessary to remove this member.

From the foregoing it is obvious that, among others, those objects specifically aforementioned are accomplished, and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the

scope of the invention which as a matter of language might be said to fall therebetween.

Having described my invention, what I claim as new and desire to secure by Letters Patent is:

1. A closure, including, in combination, a cap having a depending skirt and a split band encircling said skirt and having its body corrugated to provide an expansible portion, the ends of said band being adapted to be drawn towards each other to an extent sufficient to stretch said expansible portion, and means forming a part of the band ends whereby they may be interlocked. 70

2. A closure, including, in combination, a cap having a depending skirt and a split band encircling said skirt, the ends of said band being drawn together and interlocked permanently by non-restorable deformation of one of said ends, the interlocked ends of the band presenting a space adapted to receive an implement to rupture the same. 80

3. A closure member, including, in combination, a receptacle presenting a mouth, a cap adapted to close said mouth, a split band 90 adapted to embrace said cap, the ends of said band permanently being locked together, said band having its ends destructibly separable in order to open said closure.

4. A closure, including, in combination, a cap having a depending skirt and a split band encircling said skirt, offset end-portions forming a part of said band, one of said portions presenting an opening, a collar forming a part of the second end-portion thereof and 100 adapted to be extended through said opening and to have its outer end subsequently deformed to prevent a separation of said ends. 95

5. A closure, including, in combination, a cap having a depending skirt and a split band 105 encircling said skirt, offset end-portions forming a part of said band, reinforcing flanges extending between the band body and the end-portions, and means forming a part of one of said end-portions and adapted to engage the 110 second end-portion and to be subsequently deformed to normally prevent a detachment of said end-portions. 110

6. As an article of manufacture, a closure band, including a body adapted to be applied 115 to a receptacle, and a non-resilient, permanently stretchable portion forming an integral part of said body.

7. As an article of manufacture, a closure band, including a body adapted to be applied 120 to a receptacle, and corrugated substantially non-resilient portions forming a part of said band and providing means whereby said band may be accommodated to different sizes of receptacle portions. 125

8. A closure, including a body comprising integral non-resilient permanently stretchable and non-stretchable portions.

9. A closure for receptacles, including, in combination, a cap having a downwardly-ex- 130

- tending skirt and a locking band disposed to encircle said skirt, the ends of said band extending substantially at right angles to the body thereof, means forming a part of said ends and joining the same, said means presenting a substantially flat face engaging the corresponding face of one of the band ends for locking the same against relative movement.
10. A closure for receptacles, including, in combination, a cap having a downwardly-extending skirt and a locking band disposed to encircle said skirt, the ends of said band extending substantially at right angles to the body thereof, and means, forming a part of one of said ends, to be extended through an opening in the second end and deformed at a point beyond said opening to present a flat face in contact with the corresponding face of the second band end to prevent a separation of the band ends.
15. A closure for receptacles, including, in combination, a cap having a downwardly-extending skirt, a single band having a non-resilient body disposed around the outside of said skirt and being initially of insufficient length to encircle the same, said band having a deformed portion whereby it may be elongated sufficiently to encircle the same, and means forming an integral part of the band ends for directly connecting the same.
20. A closure for receptacles, including a split band to be applied around the skirt of a cap to retain the same in position upon a receptacle, the ends of said band being forcibly drawn towards each other, and means forming a part of said ends for non-restorably interlocking the same, said means being operable by deforming the same with the band ends in contact.
25. A milk bottle closure, including, in combination, a cap having a downwardly-extending skirt, said cap to be applied to the mouth of a bottle with the skirt enclosing the pouring lip thereof, a split band disposed around said skirt and having portions of its body corrugated, the ends of said band extending at an angle to the body thereof and one of said ends being formed with an opening, a hollow stud extending outwardly from the second end of said band, the band being of initially insufficient length to encircle said skirt and being adapted to be extended to have said stud extend through the opening, said stud being subsequently deformed to prevent a detachment of the band ends.
30. A closure, including a skirted cap, a split band encircling the outer face of the cap skirt, and means associated with the end portions of said band for interlocking permanently such end portions by deforming the same, the removal of said band being effected by a destruction of portions thereof.
35. A closure, including, in combination, a cap having a central expandible cup portion and a depending skirt, a split band encircling the outer face of said skirt, said band including a body having a normally constricted portion and being of a length insufficient to enclose said skirt, said band ends being drawn into contact with each other, and said constricted portion being permanently expanded during such drawing action, the force required for said expanding being such that the skirt of said cap is drawn downwardly over the pouring lip of the receptacle to be sealed and the cup portion of said cap is expanded, and means at the ends of said band for interlocking the same permanently after the completion of such expansion.
40. As an article of manufacture, a split band adapted for use in sealing bottle caps and the like, comprising a strip of metal having its ends extending outwardly in the same direction at substantial right angles to the face of the band; one of said ends being formed with an opening and the other of said ends being formed with a protrusion adapted to be inserted through said opening and deformed to secure the ends of the band together.
45. As an article of manufacture, a split band adapted for use in sealing bottle caps and the like, comprising a strip of metal having its ends extending outwardly in the same direction at substantial right angles to the face of the band; one of said ends being formed with an opening, and the other of said ends having a protruding collar adapted to be inserted through said opening and deformed to secure the ends of the band together.
50. As an article of manufacture, a split band adapted for use in sealing bottle caps and the like, comprising a strip of metal having its ends extending outwardly in the same direction at substantial right angles to the face of the band, rigidifying means between the body of said band and the outwardly-extending ends; one of said ends being formed with an opening, and the other of said ends being formed with a protrusion adapted to be inserted through said opening and deformed to secure the ends of the band together.
55. As an article of manufacture, a split band adapted for use in sealing bottle caps and the like, comprising a strip of metal having its ends extending outwardly in the same direction at substantial right angles to the face of the band; said band including transverse corrugations which shorten the effective length thereof; and one of said ends being formed with an opening and the other being formed with a protrusion adapted to be inserted through said opening and deformed to secure the ends of the band together.
60. As an article of manufacture, a split band adapted for use in sealing bottle caps and the like, comprising a strip of metal having its ends extending outwardly in the same direction at substantial right angles to the face of the band, rigidifying means between the body of said band and the outwardly-extending ends; one of said ends being formed with an opening, and the other being formed with a protrusion adapted to be inserted through said opening and deformed to secure the ends of the band together.
65. As an article of manufacture, a split band adapted for use in sealing bottle caps and the like, comprising a strip of metal having its ends extending outwardly in the same direction at substantial right angles to the face of the band, rigidifying means between the body of said band and the outwardly-extending ends; one of said ends being formed with an opening, and the other being formed with a protrusion adapted to be inserted through said opening and deformed to secure the ends of the band together.

face of the band; said band being partially cut adjacent one of its ends whereby subsequent rupture thereof is facilitated; one of said ends being formed with an opening, and the other being formed with a protrusion adapted to be inserted through said opening and deformed to secure the ends of the band together.

21. As an article of manufacture, a split

band adapted for use in sealing bottle caps 13 and the like, comprising a strip of metal; one of the ends of said strip being formed with an opening and the other end having a protruding collar adapted to be inserted through said opening and deformed to secure the ends of 15 the band together.

In testimony whereof I affix my signature.

WILLIAM H. KNOWLES.
